UNITED STATES PATENT OFFICE.

SOLIS C. SIMON, OF PHILADELPHIA, PENNSYLVANIA.

RADIATOR-COVER FOR AUTOMOBILES.

1,260,585.

Specification of Letters Patent. Patented Mar. 26, 1918.

Application filed July 14, 1917. Serial No. 180,510.

To all whom it may concern:

Be it known that I, Solis C. Simon, a citizen of the United States, residing at Philadelphia, in the county of Philadelphia and State of Pennsylvania, have invented certain new and useful Improvements in Radiator-Covers for Automobiles, of which the following is a specification.

My invention consists of an improved 10 radiator cover for automobiles. One object of my invention is to provide a cover of the above described type so that it will be adjustable to neatly fit radiators of various widths and shapes.

15 Another object is to so make my improved cover that it can be easily and quickly attached to and removed from the radiator of an automobile.

A further object is to make my invention 20 of simple construction and so that it can be manufactured and sold at a low price.

These objects, and other advantageous ends which will be described hereinafter, I 25 attain in the following manner, reference being had to the accompanying drawings in which

Figure 1 is a perspective view of the front portion of an automobile having my improved cover thereon.

30 Fig. 2 is a front end elevation of my improved cover.

Fig. 3 is an enlarged fragmentary section taken on the line 3—3 of Fig. 2.

Fig. 4 is a view of similar nature to Fig. 35 2 showing the radiator curtain rolled up and supported in its rolled position.

Fig. 5 is an enlarged fragmentary perspective view of a portion of my invention.

40 Fig. 6 is a fragmentary perspective view looking from the inside of the cover.

Fig. 7 is a fragmentary elevation of a slightly modified form of my invention.

Referring to the drawings, 1 represents 45 my improved cover, the major portion of which is preferably made of waterproof cloth. The portion 2 is designed to cover the hood and the top of the radiator. This portion 2 has wings 3 sewed to the front edges thereof which are designed to extend partway across the front of the radiator. In other words, these wings 3 extend substantially at right angles to the portion 2 and embrace the front side edges of the 55 radiator.

A curtain 4 is sewed or otherwise secured

to the front top edge of the portion 2 and hangs therefrom. The curtain 4 is made of a greater width between its side edges 5 than the distance between the two inner 60 edges 6 of the wings 3. Thus, the edges 5 normally overlap the wings 3 as clearly shown in Figs. 2 to 5 inclusive. The top edges 7 of the overlapping portions of the curtain 4 are preferably beveled and are 65 free of the hood 2. These edges are preferably formed by cutting the curtain and turning the edge inwardly as shown in Fig. 6.

The curtain 4 is secured between the upper 70 portions of the edges 7 to the front edge of the portion 2 by stitching or other suitable means. The side edges of the curtain 4 have plates 8 pivotally secured thereto by pins or rivets 9. Each of these plates has a series 75 of slots 10 formed therein at various distances from the pivot point. Hooks 11 are secured adjacent the junction of the portion 2 and wings 3. These hooks are designed to engage the slots 10 to place tension on 80 the curtain and on the sides of the portion 2.

The hooks 11 and plates 8 form adjustable clamps to permit the cover to be pulled taut to neatly fit various widths and shapes of 85 hoods and radiators, since it will be noted that if a narrow hood and radiator is encountered, the hooks 11 can be placed in the slots which are nearest the pivotal axis of the plates, thus securing a greater amount 90 of overlap between the edges 5 and the wings 3. The plates 8 being pivoted to the curtain 4, can assume angular positions to take up for any vertical or longitudinal movement necessary between the curtain and the 95 side wings.

To permit the curtain 4 to be rolled up, the curtain on its front face is provided with a hook 12 similar to the hooks 11 above described and a securing strap 13 is secured at 100 its upper end to the rear surface of the curtain 4. The lower end of the securing strap is provided with a plate 14 of the same general construction as the plates 10 so that after the curtain has been rolled into the 105 position shown in Figs. 1 and 4, the strap 13 can be turned into a position to engage the hook 12 by the plate 14.

I provide an auxiliary strap 15 to hold the bottoms of the wings 3 together when the 110 curtain 4 is rolled up. This auxiliary strap at its opposite ends is provided with plates

16 which are similar to the plates 10, and the lower ends of the wings 3 are provided with hooks 17 designed to engage the slots in the plate 16, and thereby retain the bottom of the hood cover in position while the curtain is rolled.

The form of my invention shown in Fig. 7 is substantially similar to the construction above described with the exception that the 10 side wings, corresponding to the wings 3, are eliminated and the auxiliary strap 18 extends directly between and is connected to the front edges of the portion 2. In all other respects the structure shown in Fig. 15 7 is similar to that described in connection with Figs. 1 to 6 inclusive, and I have therefore given similar parts corresponding reference numerals.

By the above description, it will be noted that the curtain 4 is only secured throughout a portion of its width to the portion 2, hence the side portions of the curtain are free to the extent of the length of the edges 7. This is an important feature in my invention, since it allows the sides of the cover to be drawn together by the adjustable clamps without wrinkling the fabric. Furthermore, it permits the same cover to be used on hoods and radiators of various sizes and shapes and the manufacturing cost is thereby reduced to a minimum, since the manufacturers do not have to carry various size covers to suit automobiles in which there is only a slight difference in the widths 35 of the radiators and hoods.

While I have described my invention as taking a particular form, it will be understood that the various parts of my invention may be changed without departing 40 from the spirit thereof, and hence I do not limit myself to the precise construction set forth, but consider that I am at liberty to make such changes and alterations as fairly come within the scope of the appended 45 claims.

Having thus described my invention, what I claim as new and desire to secure by Letters Patent is:

1. A cover of the character described in-

cluding a portion adapted to cover the top 50 and sides of a radiator, a curtain depending from the front of said portion, adjustable clamping means for connecting the sides of the curtain to said portion, the top edge of said curtain at positions within its 55 width and adjacent its side edges being free of said first portion, the remaining portion of said top edge of the curtain being secured to the front of the top of said first portion, substantially as described.

2. A cover of the character described including a portion adapted to cover the top and sides of a radiator, a curtain at the front of said portion, adjustable clamping means for connecting the sides of the curtain to said portion and for securing them at various distances apart, means for supporting said curtain in a raised position, and adjustable means for connecting the sides at the bottom of said first portion 70 when the curtain is raised, substantially as described.

3. A cover of the character described including a portion adapted to cover the top and sides of a radiator, wings secured to 75 the front edges of the sides of said first portion and designed to extend in front of the radiator, said side wings extending downwardly from the top of said portion, a front curtain secured at its top edge to 80 the front edge of said first portion, said curtain being of a width normally sufficient to overlap said wings, the top edge portions of said overlapping part of the curtain being free of said first portion, and adjustable securing means between the sides of said curtain and the sides of said first portion, said wings being adapted to close the space between the sides of the curtain and the sides of said first portion, substantially as described.

In testimony whereof I have signed my name to this specification in the presence of two subscribing witnesses.

SOLIS C. SIMON.
